UNITED STATES PATENT OFFICE.

RALPH R. SPEARS, OF WHEELING, WEST VIRGINIA.

PLATE-HANDLING MACHINE.

SPECIFICATION forming part of Letters Patent No. 707,172, dated August 19, 1902.

Application filed June 29, 1901. Serial No. 66,574. (No model.)

To all whom it may concern:

Be it known that I, RALPH R. SPEARS, a citizen of the United States, residing at Wheeling, in the county of Ohio and State of West Virginia, have invented a new and useful 5 Plate-Handling Machine, of which the following is a specification.

This invention relates to a novel plate-handling machine, and has for its object to provide 10 a simple, effective, and automatic apparatus for removing metal plates from a plating-bath and for delivering said plates at a point removed from the bath—as, for instance, the bran-box.

15 Inasmuch as my machine is designed with special reference to the handling of metal plates coated with tin in a molten bath, it may be stated that ordinarily tin-plating is effected by passing thin iron or steel plates between pressing-rolls submerged in a bath of molten tin, upon the surface of which a heavy body of oil is floating. In manually removing the plates from the bath more or less skill is required on the part of the operator, for the reason that the plate must not be forcibly drawn away from the rolls, because in that event the plating would be imperfect, and, on the other hand, as soon as the plate is released by the rolls it must be 25 promptly lifted from the bath to prevent undue dripping, which would result in an accumulation of plating metal or tin at the lower edge of the plate. Furthermore, the fumes arising from the bath are noxious, and in consequence of the skill required in the manipulation of the plates and the injurious and disagreeable nature of the work the cost of labor is rendered a considerable item, disproportionate to the value of low-grade plates.

30 My present invention is therefore directed to the production of an automatic machine comprehending a series of carriers arranged for successive presentation above the bath and operated to lift the plates therefrom by mechanism automatically brought into action by the movement of the plate fed upwardly between the pressing-rolls, the successive presentation of the carriers into position to receive the plates being automatically effected 35 by mechanism brought into operation by the elevation of the carrier as the latter is operated to remove a plate preparatory to its

transference from a point above the bath to the point of delivery—as, for instance, above the bran-box. This arrangement of the mechanism renders the entire apparatus dependent for its operation upon the plate, so that while the latter is not drawn away from the rolls with undue force it is promptly lifted from the bath at the proper time and is then transferred to the point of delivery simultaneously with the presentation of another carrier in position to receive the next succeeding plate. 55

The present embodiment of the invention also contemplates carrier-elevating mechanism which, while serving to positively elevate the carriers, is automatically rendered inoperative in the event of undue resistance being opposed to the upward movement of the carrier—as, for instance, by the sticking or hanging of the plate emerging from the bath, so that upon the happening of an accident or the derangement of the feed of the plate the upward movement of the carrier will be automatically stopped until the resistance opposed 70 by the plate to such upward movement is again normal, at which time the carrier-elevating mechanism will become effective automatically and the handling of the plates 75 will be proceeded with. 80

My present invention also contemplates the provision of means for causing the carriers to remain in their elevated positions except when receiving or delivering a plate in order that the space occupied by the machine may 85 be economized; also, the equipment of the carriers with plate-grippers and gripper holding and releasing mechanism of novel form calculated to insure the retention of the plate against slipping out of engagement with the 90 carrier after such engagement has once been effected.

Further and subordinate objects of the invention and certain other novel features thereof will hereinafter more fully appear as 95 the succeeding description of the preferred form of my invention is developed.

In the accompanying drawings, Figure 1 is a top plan view of my plate-handling machine complete. Fig. 2 is a side elevation of the 100 subject-matter of Fig. 1. Fig. 3 is a central vertical sectional view of the machine with one of the grippers in engagement with the upper edge of the metal plate emerging from

the bath, the elevated position of the engaged carrier being shown in dotted lines. Fig. 4 is a front elevation of the machine, showing one of the carriers in section and another of said carriers broken away, the grippers of the third carrier being shown in the act of releasing a plate. Figs. 5 and 6 are sectional views, partly in elevation, of the mechanism for throwing the pinions into or out of engagement with the driving-shaft; and Figs. 7 and 8 are detail views of the pivoted trip designed to effect the automatic disconnection of the carrier-ring from the power mechanism.

Like numerals of reference are employed 15 to designate corresponding parts throughout the several views.

The production of what are known commercially as "tin plates" is effected ordinarily by passing thin plates of iron or steel 20 through a molten bath of tin, upon the surface of which is floating a heavy layer of oil. Submerged in the bath are suitable pressing-rolls, between which the coated plates pass as they are fed upwardly out of the bath. 25 These rolls serve to remove the surplus coating of plating metal from the plate and incidentally propel or feed the latter at the speed best calculated to attain the desired results. In Fig. 3 of the drawings I have illustrated a 30 plate in the act of leaving the bath, the numeral 1 indicating the bath-tank; 2, the bath; 3, the pressing-rolls, and 4 the plate. The plate-handling machine constituting an embodiment of my present invention is located 35 adjacent to the tank, at one side thereof, and is designed, as stated, to automatically remove the plates 4 from the bath and transport them to the bran-box or other removed point, where they are automatically delivered. 40 The machine comprises a substantially circular frame or bed-plate 5, upon which is rotatably mounted a carrier-ring 6, supporting a series of pivoted arms or carriers 7, 8, and 9, designed to be successively presented over 45 the bath-tank 1 by the rotation of the ring 6. This ring 6 is seated in a circular cavity 10, formed in the frame or bed-plate 5, and is retained in place by a cap-ring 11, secured to the frame 5 by bolts or other suitable fastening means 12, and the rotation of said ring is 50 effected by means of a driving-shaft 13, geared thereto—as, for instance, by means of a pinion 14, carried by the shaft and meshing with a ring gear or crown 15, formed on the under 55 side of the ring 6, said pinion being of proper size to complete one revolution during each replacement of a carrier. The driving-shaft 13 is journaled in suitable bearings 16 and 17, located below and preferably secured to the 60 frame or bed-plate 5, which latter is cut out, as indicated in Fig. 3 of the drawings, to accommodate the pinion 14, geared to the carrier-ring.

The rotary movement of the carrier-ring 6 65 to successively present the several carriers above the bath-tank 1 is necessarily intermittent, and as the proper timing of this

movement is controlled by the individual movement of the carrier located above the tank I shall first describe the construction 70 and operation of the carriers proper and will then explain the construction and arrangement of the mechanism controlled by the individual carriers to effect the intermittent movement of the carrier-ring necessary to 75 cause the successive presentation of the carriers to their positions over the bath. In Fig. 3 of the drawings one of the carriers and its operating mechanism is clearly shown, and I shall therefore describe this carrier in detail, 80 it being understood that the several other carriers are similarly constructed and operated and are equidistantly spaced upon the carrier-ring. The carrier 7 is in the form of an elongated arm or rod fulcrumed adjacent 85 to its inner or rear end, as indicated at 18, between a pair of upstanding angle-brackets 19, the foot-flanges of which are bolted to the upper surface of the ring 6 adjacent to its outer edge. At its free end this arm or carrier is provided with a fixed gripper 20 and a pivoted gripper 21, longitudinally curved to form a flaring entrance and designed to grip the upper edge of the plate 4 to enable the carrier to lift the plate from the bath as soon as 90 the latter has been released by the pressing-rolls 3. The specific form of the pivoted gripper 21 may be varied within wide limits, but by preference its upper end is disposed at an angle to the gripper proper and is bifurcated 95 (see Fig. 1) for the reception of an interposed bearing 22, formed on the carrier-arm. This upper end of the pivoted gripper, or, rather, the angular extension thereof, is thickened somewhat and constitutes a weight 23, serving 100 normally to retain the pivoted gripper in position to permit the reception of a plate between the grippers—that is to say, the weight 23 normally retains the grippers in the open position. It will be understood, however, 105 that after the plate has been presented between the grippers the latter must be urged together with considerable force in order that the plate may be held with sufficient security to insure its elevation from the bath when the 110 carrier is swung upwardly by the mechanism to be described. I therefore provide a gripper-closing device, comprising a gripper-cam 115 24, pivoted upon an angular extension 25 of the arm 7 and fixed to an arm 26, provided 120 with an adjustable weight 27. The weighted arm 26 is designed to operate the cam 24, which latter, acting upon the adjacent concaved face of the pivoted gripper 21, urges the latter with sufficient pressure to overcome 125 the resistance of the weight 23 and to cause the upper edge of the plate 4 to be securely clamped between the grippers.

As the carrier-ring is rotated to present a carrier over the bath-tank the lateral movement of said carrier presents the weighted arm 26 to an inclined trip 28, suitably supported above the bath, as indicated in Fig. 3, and as the lateral movement of the carrier

continues the arm 26, riding up the trip 28, will withdraw the cam 24 from the pivoted gripper 21 to permit the latter to move to its open position under the impulse of the grip-
5 per-weight 23. Therefore when the carrier comes to rest above the tank in position to receive a plate the grippers will be separated and the arm 26 of the cam will be supported upon the trip.

10 Inasmuch as the feed of the plates 4 from the bath is under some conditions more or less irregular, it is undesirable to provide for the regular timing of the several operations of the plate-handling machine, because in this event
15 the carrier located in position to receive a plate might, perchance, be elevated before the plate had reached a position to be held between the grippers. I therefore construct the machine in a manner to make its operation dependent
20 upon the plate, the movement of the latter as it is delivered from the bath serving, first, to secure the automatic closing of the grippers upon the plate, and, next, to start the mechanism for elevating the carrier to lift the
25 plate completely from the bath. Thus, assuming the parts to be in the position indicated in Fig. 3, the upward movement of the plate 4 from the bath presents its upper edge between the grippers, and as said edge finally
30 comes in contact with the opposed faces of the grippers adjacent to their point of convergence the plate will effect the elevation of the outer end of the carrier. The upward movement or swinging of the carrier will
35 withdraw the weighted arm 26 from the trip 28, and the gravitation of the weight 27 thus released will swing the cam 24 for the purpose of closing the pivoted gripper against the plate with sufficient force to insure the secure
40 retention of the plate in order that the latter may be raised out of the bath and transported to a remote point without danger of displacement.

45 After automatically effecting the closing of the grippers the continued upward movement of the plate will present the arcuate bearing-face 29 of a segment 30 at the rear extremity of the carrier into frictional engagement with the friction-wheel 31 of the carrier-elevating
50 mechanism, and as this wheel is positively driven in the direction of the arrow in Fig. 3 the outer end of the carrier will be elevated to withdraw the plate 4 entirely from the bath preparatory to its lateral transportation
55 through the rotation of the carrier-ring 6. At this point it should be noted that as the engagement between the carrier and its elevating mechanism is frictional any undue resistance to the upward movement of the
60 plate 4 sufficient to overcome the frictional contact between the carrier and its elevating mechanism will result in the stoppage of the carrier and all danger of the forcible withdrawal of the plate from the pressing-rolls,
65 the disengagement of the plate from the grippers, or the derangement of the mechanism will be prevented. In the event of such in-

terruption of the operation of elevating the plate the friction-wheel 31 will rotate idly in contact with the bearing-face 29 until the re-
70 sistance opposed to the upward movement of the plate 4 is sufficiently decreased, at which time the movement of the carrier 7 will be continued and the plate will be withdrawn from the bath-tank.

75 The carrier-elevating mechanism comprehends a power-transmitting shaft 32, journaled in suitable bearings 33, pendent from the frame, and keyed to said shaft is a worm-gear 34, in mesh with a worm 35 on the driving-shaft 13. Motion is communicated from the shaft 32 to the friction-wheel 31 by means of suitable gearing—as, for instance, a sprocket-wheel 36, keyed upon the shaft 32 and geared, by means of a sprocket-chain 37, with a 80 sprocket-wheel 38, disposed at one side of the friction-wheel 31 and secured thereto in any suitable manner. The driving-shaft 13 is designed to be continuously operated, and the friction-wheel 30 of the carrier-elevating 85 mechanism will therefore constantly rotate, but will not, as we have seen, be effective to elevate a carrier until the latter has been thrown into engagement therewith by the initial upward movement of the plate.

90 Inasmuch as the elevation of the carrier is designed to be automatically interrupted in the event of the improper feeding of the plate from the pressing-rolls, it is desirable to provide a plate-handling machine of the character described with mechanism by means of which the machine may be set to provide for the interruption of the elevation of the carrier when its operation is opposed by various resistances—that is to say, under some conditions it is desirable to render the mechanism comparatively sensitive, so that comparatively slight resistance to the upward movement of the plate from the bath will effect the interruption of the movement of the carrier, 95 while under other conditions it is desirable that the operation of the device be interrupted only in the event of considerable resistance being opposed thereto by the plate. For this reason the shaft of the friction-wheel 31 of the carrier-elevating mechanism is journaled in a movable frame 39, preferably in the form of a bell-crank lever, fulcrumed at its angle upon the shaft 32. The long arm 40 of this lever or frame extends 100 upwardly from the shaft 32 through a central or axial opening 41 in the machine-frame or bed-plate 5 and supports at its upper free end the wheel 31, while the opposite or short arm 42 of the bell-crank frame 39 extends 105 horizontally under the machine and is connected with suitable tension mechanism 43, opposing the swinging of the frame 39 and the recession of the wheel 31 from the arcuate bearing-face 29 of the adjacent carrier.

110 The tension mechanism 43 is a reactive device, preferably in the form of a spring, secured at one end to the under side of the frame 5 for the machine and at its opposite

end to an endwise-adjustable eyebolt 44, passed through the arm 42 and provided upon its lower end with a nut 45, by means of which the tension of the spring may be adjusted. It will therefore appear that the friction-wheel 31 of the carrier-elevating mechanism is urged into contact with the adjacent arcuate bearing-face of the carrier by yielding tension mechanism adjustable to increase or diminish the frictional contact between the parts, so that the operator may determine the degree of resistance to the elevation of the carrier necessary to effect the automatic interruption of such movement.

We have now seen the manner in which the initial movement of the plate 4 as it emerges from the bath effects the automatic closing of the grippers and the bringing of the carrier-elevating mechanism into operation; also, in what manner provision is made for positively elevating the carrier subsequently to the initial elevation of the plate by the pressing-rolls and for interrupting such elevation in the event of the opposing of undue resistance to such movement. It has also been premised that the simultaneous movement of the several carriers to present them successively at the receiving and delivering points is effected by the intermittent rotation of the ring 6, and I shall now proceed to describe the mechanism by means of which this intermittent movement of the carrier-ring is automatically inaugurated by a loaded carrier and is automatically discontinued when the next carrier has reached a point above the bath.

The pinion 14 is loosely mounted on the shaft 13, and to its hub is secured by any suitable means a sleeve 46, encircling a collar 47, keyed upon the shaft and provided with a series of peripheral teeth 48, designed to be engaged by a spring-pressed pawl 49, mounted for reciprocation within a cylindrical pawl-casing 50, tapped into the sleeve 46 and provided with diametrically opposite longitudinal slots 51 for the reception of the opposite ends of the pin 52, passing through the pawl and having one end extended beyond the pawl-casing to form a stud or projection 53 for a purpose to be described. The teeth 48 are not continued entirely around the collar, for the obvious reason that said collar is always in substantially the same position when engaged by the pawl. The pawl 49 is pressed inwardly toward the collar 47 by the spring 54, the tension of which is regulated by a screw-plug 55 closing the upper end of the casing 50. When the pawl 49 is in its depressed position, as shown in Figs. 5 and 6, it engages the teeth in the collar 47 and effects an operative connection between said collar and the pinion 14 through the sleeve 46. Therefore when the pawl is depressed the carrier-ring 6 will be rotated to transport the carriers simultaneously from one point to another. The intermittent rotation of the carrier-ring is designed, however, to cease

whenever a carrier is presented over the tank 1, and to accomplish this result it is simply necessary to provide means for automatically retracting the pawl 49 when a carrier has reached a position to receive a plate 4 from the bath. Various forms of mechanisms may be provided for this purpose; but I prefer to employ a swinging trip member 56, (see Figs. 2, 3, 7, and 8,) pivoted upon the bearing 16 and provided with a pawl-retracting cam 57, at the rear end of which is disposed a stop-lug 58, against which the projecting end 56 of the pin 52 abuts after the pin has moved over the cam 57 to effect the retraction of the pawl 49 from engagement with the collar 47. Thus as the driving-shaft 13, the pinion 14, the sleeve 46, and collar 47 rotate in unison to drive the carrier-ring 6 the carrier will be advanced over the tank 1 to receive a plate 4, and just as the carrier reaches its position to receive said plate the projecting end 56 of the pawl-pin will ride up the pawl-retracting cam to disconnect the pinion 14 from the driving-shaft, and thereby arrest the movement of the carrier-ring 6, the interposition of the stop 58 in the path of the pin serving to prevent the momentum gained by the carrier-ring 6 from moving the carrier beyond its proper position after the ring has been disconnected from the driving-shaft. It will now be obvious that in order to start the carrier-ring again it is simply necessary to swing the trip member 56 to the dotted position shown in Fig. 3 for the purpose of retracting the cam 57 from under the projecting end of the pawl-pin to permit the pawl to again drop into engagement with the collar 47, rotating with the driving-shaft.

I have stated that the movement of the carrier-ring is controlled by the individual carriers, which are designed to automatically start the ring when a loaded carrier has reached its elevated position. A simple device for effecting this operative connection between the carriers and the driving mechanism therefor comprehends a trip-lug 59, extending from the carrier adjacent to its rear end and designed when said carrier reaches its elevated position to strike against the angular extremity 60 of the stop-ring 56 and to swing said member rearwardly against the resistance of the spring 61 to release the pawl. It will therefore be impossible for the machine to be operated to move the carriers laterally, or rather, horizontally, until the loaded carrier has reached its elevated position, and the accidental movement of the carrier-ring before the carrier has fully retracted the plate from the bath and above the tank will be prevented. The device as thus far described is completely operative, since it comprehends mechanism for engaging a plate, for lifting it from the molten bath, and for transporting it to the point of delivery, where it is automatically released by a trip 62, similar to the trip 28 and likewise designed to elevate the weighted arm 26 of the gripper-cam 24; but as a

large number of machines of this character are usually employed in a plant economy of space is a desideratum, and I therefore prefer to employ means for holding the carriers in their upright positions, except at those points where the plates are received and delivered. One form of such means is shown in the drawings and comprehends an upstanding carrier-supporting cam-flange 63, cut away at the front of the machine, as best seen in Fig. 4, and formed at one side of the cut-away portion with an abruptly-inclined face 64, down which the carrier gravitates just before reaching its position over the bath and with such rapidity as to elevate the rear end of the carrier out of the way of the friction-wheel 31 before the carrier is swung to a position directly opposite the periphery of said wheel. Opposite the point of delivery the cam-flange is provided with a depression 66, defined between two oppositely-inclined cam-faces 67 and 68, and each of the carriers is provided with an antifriction-roller 69, designed to travel along the upper edge of the cam-flange 63.

In brief, the operation of my device is as follows: Assuming the parts to be in the positions indicated in Fig. 3 of the drawings, the plate 4 emerging from the bath will engage the grippers, and its upward movement will first effect the closing of the grippers by withdrawing the arm 26 from the trip 28 and will then elevate the carrier 7 sufficiently to bring the bearing-face thereof into contact with the friction-wheel 31 of the carrier-elevating mechanism. The carrier-elevating mechanism being constantly operated will now swing the carrier upon its fulcrum to continue the withdrawal of the plate 5 from the bath unless the resistance to the movement of said plate is sufficient to overcome the frictional contact between the carrier and its elevating mechanism. The continued elevation of the carrier will dispose it in an upright position, as indicated in Fig. 2 of the drawings, and will present the trip-lug 57 to the pivotal trip 56 and swing the latter to release the pawl 49, and thereby effect an operative engagement between the carrier-transferring mechanism and the driving mechanism. The carrier-ring comprehending the primary element of the carrier-transferring mechanism will now be rotated to transfer the loaded carrier from a point above the bath to the point of delivery. During this movement of the ring the antifrictional roller 69 of the carrier 7 will ride upon the upper edge of the cam-flange 63, and as the bearing-face 29 of the carrier will now have moved out of engagement with the friction-wheel 31 said carrier is free to swing downwardly to a horizontal position as the roller 69 travels down the inclined face 67 of the cam-flange. When the carrier reaches the bottom of the depression 66, as shown in Fig. 4 of the drawings, the arm 26 will have contacted with and moved up the trip 62, and the plate will be released and per-

mitted to drop—as, for instance, into the branox. (Not illustrated.) Continued movement of the ring will now cause the carrier 7 to again assume its upright position by the travel of its antifriction-roller 69 up the inclined face 68 of the cam-flange. By the time the carrier 7 has reached this position—that is to say, the position in which the arm 8 is shown in Fig. 3—the arm 9 will have reached the abrupt inclined face 64 and will have moved down the latter, assuming the position which the carrier 7 occupies in Fig. 3, the downward movement of its free end being limited by a suitable rest 70, supported, for instance, upon the tank 1. During the travel of the carriers from the upper end of the inclined face 68 to the inclined face 64 said carriers will be maintained in their upright positions, and it will thus appear that while space is economized by transferring the carriers in their upstanding or upright positions provision is made for lowering the carriers to their depressed positions at the receiving and delivering points and for their elevation after they have received or delivered a plate, as the case may be.

It is thought that from the foregoing the construction and operation of my machine will be clearly apparent; but while the present embodiment of the invention is believed at this time to be preferable I desire to reserve the right to effect such changes, modifications, and variations of the illustrated structure as may be suggested by experience and experiment and embraced within the scope of the protection prayed.

What I claim is—

1. In a plate-handling machine of the character described, the combination with a support, of a plurality of plate-carriers movable therewith, and provided with gripping devices for engaging the edge of a plate, and means for imparting intermittent movement to said support to effect the successive presentation of the carriers in position to receive a plate.

2. In a plate-handling machine of the character described, the combination with a movable support, of a plate-carrier movable therewith, and independently movable thereon, and means controlled by the independent movement of the plate-carrier for effecting the movement of the support.

3. In a plate-handling machine of the character described, the combination with a vertically-movable plate-carrier arranged to lift a plate from a bath, of carrier-transferring mechanism for moving the carrier horizontally from the receiving-point to the delivering-point, said transferring mechanism being controlled by the vertical movement of the carrier.

4. In a plate-handling machine of the character described, the combination with a movable support, of a plate-carrier independently movable thereon, and means controlled by

the individual movement of the carrier for effecting the intermittent movement of the support.

5. In a plate-handling machine of the character described, the combination with a movable support, of an independently-movable plate-carrier mounted thereon, and equipped with a gripping device disposed to grip the edge of a plate, means for effecting the independent movement of the plate-carrier, and means for operating the support to transfer the carrier from the receiving-point to the point of delivery.

6. In a plate-handling machine of the character described, the combination with a movable support, of a plate-carrier independently movable thereon, means for imparting independent movement to the plate-carrier, and means for moving the support to transfer the carrier from the receiving-point to the point of delivery, said last-named means being controlled by the independent movement of the carrier.

7. In a plate-handling machine of the character described, the combination with a movable support, of a pivoted plate-carrier mounted thereon, means for swinging said plate-carrier upon its pivot to lift a plate from the bath, and means for moving the support to transfer the carrier to the point of delivery.

8. In a plate-handling machine of the character described, the combination with a movable support, and a swinging plate-carrier movable therewith, of driving mechanism, gearing intermediate of the driving mechanism and carrier, to swing the latter for the purpose of lifting a plate from the bath, and independent gearing between the driving mechanism and support for moving the latter to transfer the carrier to the point of delivery.

9. In a plate-handling machine of the character described, the combination with a movable support and a plate-carrier mounted thereon for independent movement, of driving mechanism, a trip device controlling the operative connection between the driving mechanism and support, and means for operating said trip device through the independent movement of the carrier.

10. In a plate-handling machine of the character described, the combination with a movable support, driving mechanism and a trip device controlling the operative engagement between the driving mechanism and support, of a swinging plate-carrier mounted on the support and arranged to operate the trip device, and means for swinging said carrier.

11. In a plate-handling machine of the character described, the combination with a movable support, of a plurality of independently-movable plate-carriers movable therewith, and means for imparting an intermittent movement to the support to effect the successive presentation of the carriers in position to receive a plate.

12. In a plate-handling machine of the character described, the combination with an in-

termittently-movable support and operating mechanism therefor, of a plurality of plate-carriers movable with the support to effect the successive presentation of said carriers in position to receive a plate, and means for elevating said carriers to lift the plate from the bath.

13. In a plate-handling machine of the character described, the combination with an intermittently-movable support, and means for imparting such movement thereto, of a plurality of plate-carriers movable with the support and capable of independent movement thereon, said plate-carriers being designed for successive presentation in position to receive a plate by the intermittent movement of the support, and carrier-elevating mechanism located opposite the receiving-point for presentation to the carriers successively.

14. In a plate-handling machine of the character described, the combination with an intermittently-movable support, a trip device controlling the movement thereof and means for moving said support, of a plurality of carriers movable with the support and capable of movement independently thereof, means for operating the trip device by each of the carriers successively to effect the intermittent movement of the support, and means for successively elevating the carriers to cause them to withdraw the plates from the bath.

15. In a plate-handling machine of the character described, the combination with a movable carrier designed to engage and remove a moving plate from the bath, of carrier-operating mechanism disposed to be engaged by the carrier through the initial movement of the latter under the impulse of the moving plate.

16. In a plate-handling machine of the character described, the combination with a swinging plate-carrier disposed for engagement with a moving plate, of carrier-elevating mechanism arranged in the path of the carrier and designed for operative engagement therewith, as the carrier is swung under the impulse of the moving plate.

17. In a plate-handling machine of the character described, the combination with a movable plate-carrier, and carrier-operating mechanism for moving the carrier to remove a plate, of means for effecting the operative disconnection of the plate-carrier from its operating mechanism when undue resistance is opposed to the movement of the carrier.

18. In a plate-handling machine of the character described, the combination with a movable plate-carrier, of carrier-operating mechanism in frictional engagement therewith, whereby the movement of the carrier will be stopped when undue resistance is opposed thereto, said carrier-operating mechanism serving to move the carrier for the purpose of withdrawing the plate from the bath.

19. In a plate-handling machine of the character described, the combination with a movable plate-carrier, of carrier-operating mechanism comprising a friction-wheel having fri-

5 tional contact with the carrier to operate the same, and means for yieldingly urging said elements into frictional engagement, said carrier-operating mechanism serving to move the carrier for the purpose of withdrawing the plate from the bath.

10 20. In a plate-handling machine of the character described, the combination with a swinging plate-carrier, of carrier-elevating mechanism comprising a friction-wheel disposed for contact with the carrier to elevate the same, and adjustable tension mechanism for yieldingly urging the friction-wheel into contact with the carrier.

15 21. In a plate-handling machine of the character described, the combination with a swinging plate-carrier, provided with a segment having an arcuate bearing-face, of carrier-elevating mechanism comprising a movable frame, a friction-wheel mounted on the frame and disposed for engagement with the bearing-face of the carrier, means for rotating said wheel to effect the elevation of the carrier, and tension mechanism connected to the frame.

25 22. In a plate-handling machine of the character described, the combination with a movable support, driving mechanism and means for effecting the intermittent engagement of the support with the driving mechanism, of a swinging plate-carrier mounted upon the support, a friction-wheel disposed to contact with the carrier to effect the swinging thereof, and gearing intermediate of the driving mechanism and said friction-wheel.

30 23. In a plate-handling machine of the character described, the combination with a movable support, driving mechanism, and means for effecting the intermittent engagement of the driving mechanism with the support, of a swinging plate-carrier mounted on the support and provided with an arcuate bearing-face, a friction-wheel disposed to engage with said bearing-face, a movable frame supporting said wheel, tension mechanism for urging the friction-wheel into engagement with the carrier, and gearing intermediate of the friction-wheel and driving mechanism.

45 24. In a plate-handling machine of the character described, the combination with a frame and a carrier-ring rotatably mounted thereon, of a plurality of plate-carriers mounted upon the carrier-ring, and means for imparting an intermittent movement to the ring to effect the successive presentation of the carriers in position to receive a plate.

50 25. In a plate-handling machine of the character described, the combination with a supporting-frame, of a carrier-ring rotatably mounted thereon, a plurality of independently-movable carriers mounted upon the ring, means controlled by the carriers for imparting intermittent movement to the carrier-ring, and means for imparting independent movement to the carriers.

55 26. In a plate-handling machine of the character described, the combination with a sup-

porting-frame, of a carrier-ring rotatably mounted thereon, plate-carriers supported by the ring and disposed radially with respect thereto, and means for rotating the carrier-ring to effect the successive presentation of the carriers in position to receive a plate.

60 27. In a plate-handling machine of the character described, the combination with a supporting-frame, and a carrier-ring rotatably mounted thereon, of a series of swinging radially-disposed plate-carriers mounted on the ring for movement therewith, means for successively elevating the plate-carriers, and means for intermittently operating the carrier-ring.

65 28. In a plate-handling machine of the character described, the combination with a carrier-ring and plate-carriers mounted thereon, of a driving-shaft, a pinion loosely mounted on said shaft for engagement with the carrier-ring, a pawl for effecting an operative engagement between the pinion and shaft, and means for automatically operating the pawl intermittently to effect the intermittent operation of the carrier-ring.

70 29. In a plate-handling machine of the character described, the combination with a carrier-ring, and plate-carriers mounted thereon, of a driving-shaft, a pinion mounted loosely on the shaft and disposed to engage the carrier-ring, a pawl arranged to effect an operative engagement between the pinion and the driving-shaft and provided with a projection, and a pivoted trip provided with a cam designed to engage said projection for the purpose of moving the pawl.

75 30. In a plate-handling machine of the character described, the combination with a carrier-ring and an independently-movable plate-carrier mounted thereon, of a driving-shaft, a pinion loosely mounted on said driving-shaft and disposed for engagement with the carrier-ring, a pawl arranged to effect an operative engagement between the pinion and driving-shaft, said pawl being provided with a projection, and a pivoted trip provided with a cam disposed to engage the projection for the purpose of operating the pawl to release the pinion from the driving-shaft, said pivoted trip being disposed for actuation by a plate-carrier to permit the pawl to move to its engaging position.

80 31. In a plate-handling machine of the character described, the combination with a carrier-ring, and plate-carriers thereon, of driving mechanism, a spring-pressed pawl controlling the engagement of the driving mechanism with the carrier-ring, said pawl being provided with a projection, a pivoted trip provided with a pawl-elevating cam and a stop-flange located at one end of the cam, and means for swinging the trip out of engagement with the projection through the movement of a carrier.

85 32. In a plate-handling machine of the character described, the combination with a carrier-ring and plate-carriers mounted thereon,

of a driving-shaft, a pinion loosely mounted on the shaft and disposed to engage the carrier-ring, a sleeve fixed to the pinion, a spring-pressed pawl carried by the sleeve, a toothed 5 collar fixed to the driving-shaft and disposed for engagement with the pawl, and means for operating the pawl to effect its engagement with and disengagement from said collar.

33. In a plate-handling machine of the character described, the combination with a movable support and a pivoted plate-carrier mounted thereon, of means for swinging said carrier to an upright position, and means for sustaining said carrier in its upright position 10 except at the receiving-point and the point of delivery.

34. In a plate-handling machine of the character described, the combination with a supporting-frame, and an upstanding cam-flange, 20 of a rotary carrier-ring mounted on the frame, and a plurality of swinging plate-carriers movable with the ring and resting on the cam-flange.

35. In a plate-handling machine of the character described, the combination with a supporting-frame and a cam-flange upstanding therefrom, said flange being cut away and provided with an abrupt inclined face adjacent to the receiving-point and provided with 25 a depression defined by oppositely-disposed inclined faces opposite the delivering-point, a carrier-ring rotatably mounted upon said frame, swinging plate-carriers movable with the carrier-ring and designed to rest upon the cam-flange during the travel of the carrier-ring, and carrier-elevating mechanism located 35 opposite the receiving-point.

36. In a plate-handling machine of the character described, the combination with a movable plate-carrier, of a pair of relatively movable grippers, a movable cam disposed to urge the grippers together, and means for operating the cam.

37. In a plate-handling machine of the character described, the combination with a plate-carrier and relatively movable grippers, of a cam disposed to urge one of the grippers toward the other, and a weighted arm connected to said cam to move the same.

38. In a plate-handling machine of the character described, the combination with a movable plate-carrier provided with grippers, of a cam disposed to urge the grippers together, and means for automatically operating the 55 cam through the movement of the carrier.

39. In a plate-handling machine of the character described, the combination with an intermittently-moving support and a plate-carrier provided with a fixed gripper and with a 60 movable gripper, said movable gripper being provided with a weight disposed to urge it to its open position, of means for moving said movable gripper toward the fixed gripper in opposition to the weight.

40. In a plate-handling machine of the character described, the combination with a plate-

carrier provided with a fixed gripper and with a movable gripper, said movable gripper being provided with a weight disposed to move it to its open position, a cam opposed to the 70 movable gripper to move said gripper to its closed position, and a weighted arm connected to the cam to operate the same.

41. In a plate-handling machine of the character described, the combination with a support, of a movable plate-carrier provided with grippers designed to engage a moving plate emerging from the bath, carrier-elevating mechanism, means for automatically closing the grippers through the movement of the 75 plate to be handled, and means for effecting an operative connection between the carrier and carrier-elevating mechanism through the continued movement of the plate after the closing of the grippers.

42. In a plate-handling machine of the character described, the combination with a supporting-arm, of a movable plate-carrier provided with grippers designed to engage a moving plate emerging from the bath, carrier-elevating mechanism, means for automatically closing the grippers through the movement of the plate to be handled, means for effecting an operative connection between the carrier and carrier-elevating mechanism through 80 the continued movement of the plate after the closing of the grippers, transferring mechanism for transferring the carriers from the receiving-point to the point of delivery, and means for starting said transferring mechanism through the movement of the carrier under the impulse of the carrier-elevating mechanism.

43. In a plate-handling machine of the character described, the combination with a rotary support, of a plurality of plate-carriers mounted on the support for movement therewith as the support is rotated, said carriers being also mounted for movement independently of the support to lift a plate from the bath 105 while the support is at rest, and means for rotating the support to present the carriers successively in the receiving position.

44. In a plate-handling machine of the character described, the combination with a movable support, of a plurality of independently-swinging plate-carriers mounted on the support for movement therewith, means for swinging the carriers to effect their elevation for the purpose of lifting the plates from the 110 bath, and means for moving the support to effect the successive presentation of the carriers to the receiving-point.

45. In a plate-handling machine of the character described, the combination with a rotary 115 support, of a plurality of plate-carriers independently pivoted upon said support and disposed radially with respect thereto, means for effecting the independent swinging of the carriers, and means for rotating the support 120 to present the carriers successively at the receiving-point.

46. In a plate-handling machine of the character described, the combination with a movable support, of a plurality of independently swinging plate-carriers mounted thereon, and 5 grippers mounted at the outer ends of the said carriers to engage the plates, said plates being first elevated by the swinging of the carriers and subsequently transferred by the movement of the support.
47. In a plate-handling machine of the character described, the combination with a movable support, and means for moving the same, of a plurality of independently - swinging plate - carriers provided with grippers and 15 mounted on the support for movement therewith, and means operated by the carriers for effecting the movement of the support.
48. In a plate-handling machine of the character described, the combination with a support mounted to rotate around a vertical axis, 20 of a plurality of radially-disposed plate-carrying arms independently pivoted upon said support and provided with grippers at their outer ends, means for rotating the support, and mechanism controlled by said arms for 25 operatively connecting said means with the support.

In testimony that I claim the foregoing as my own I have hereto affixed my signature in the presence of two witnesses.

RALPH R. SPEARS.
